UNITED STATES PATENT OFFICE

2,572,615

SAFETY DEVICE FOR BATHTUBS

Knut L. Hansen, Antioch, Calif.

Application October 19, 1949, Serial No. 122,269

1 Claim. (Cl. 4—185)

1

This invention relates to a safety device for bathtubs.

An object of this invention is the provision of an efficient device to prevent a person from slipping or falling while getting in and out of a bathtub.

Another object of the invention is the provision in a safety device of an adjustable hand grip, whereby the device can quickly be adjusted to accommodate a tall or a short person.

A still further object of the invention is to provide two lines, one of which has a hand grip permanently fastened to its lower end, while the other line has an adjustable hand grip that can be moved up or down on its line to accommodate different sized persons using the device in connection with a bathtub.

Another object of the invention is the provision in a safety device of a clamp device that performs the dual function of keeping the two lines of the device in a convenient, assembled position and making it possible to adjust on one line a hand grip, whereby different height persons can be accommodated while using the same safety device.

With the foregoing and other objects in view, this invention comprises certain novel constructions, combinations, and arrangements of parts as will be hereinafter fully described, illustrated in the accompanying drawings, and more particularly pointed out in the appended claim.

In the drawings:

Figure 1 is a view in elevation of a safety device constructed in accordance with the present invention.

Figure 2 is an enlarged, fragmentary view of the safety device, showing the clamp device in vertical, longitudinal section.

Referring to the drawings, in which the preferred embodiment of my invention is illustrated, 1 designates a line support, which is provided at its upper end 2 with a broad portion so that the line device 1 can be easily placed in the hook 3, which hook is shown in a ceiling 4. The lower end of the line support 1 is reduced in width, as at 5. To this reduced portion 5 are fastened primary line 6 and auxiliary line 7.

On the lower end of the primary line 6 is permanently secured a primary hand grip 8. This hand grip 8 is shown as a ring.

A clamp device 9 is provided with a vertical aperture 10, through which primary line 6 freely moves. The clamp device 9 is also provided with an elongated opening 11, through which the auxiliary line 7 extends. In the elongated opening

2

11 is a locking cam 12 that is pivotally mounted at 13 upon the clamp body 14. An auxiliary hand grip 15 has its stem 16 extending through the body 14 as shown, Fig. 2. A head 17 is formed on the stem 16, whereby the auxiliary hand grip 15 is permanently secured to the clamp device 9.

To adjust the hand grip carrying clamp device, all that the operator needs to do is to grasp 10 in one hand the clamp device 9 and pull downward on the lower end of the auxiliary line 7, or press upwardly on the outer end of the locking cam 12, whereupon the clamp device can be adjusted to any position. As the auxiliary 15 hand grip 15 is carried by the clamp device 9, any adjustment of the clamp device upon the auxiliary line 7 will likewise adjust said auxiliary hand grip 15. In this way, the hand grip 15 can be adjusted to suit the height of the 20 person using the bathtub 18.

The clamp device 9 keeps the two lines in close assembled position, whereby the two hand grips 8 and 15 are ready for the bather to grasp.

By the term "line" is meant any equivalent 25 cord or rope, or the like, that will answer for the elements of this device.

It will be apparent that when the clamp device 9 has been adjusted to suit the operator, all the person has to do is to pull slightly downward upon the auxiliary hand grip 15, whereupon the locking cam 12 will immediately grip the auxiliary line 7, securely holding the clamp device 9 in the desired adjusted position.

While I have described the preferred embodiment of the invention and illustrated the same 35 in the accompanying drawings, certain minor changes or alterations may appear to one skilled in the art to which this invention relates during the extensive manufacture of the same, and I, therefore, reserve the right to make such changes or alterations as shall fairly fall within the scope 40 of the appended claim.

What I claim is:

In a device of the kind described, a line support, a flexible line having its upper end fixedly attached to said support, a hand grip attached to the lower end of said line for holding the line tense, a clamp body having an opening therethrough for said line, said clamp body being 50 freely slideable on said line, an auxiliary line having its upper end fixedly attached to said support, said body having an opening through which said auxiliary line passes, a hand grip fixed beneath said body for moving the body 55 along said lines, the opening in the body being

laterally elongated to form a slot, a gravity actuated cam grip pivotally mounted in said slot and normally gripping said auxiliary line, and a finger piece carried by said grip and projecting from the slot for manipulation to resist said grip from the auxiliary line.

KNUT L. HANSEN.
